JOSEPH ASKIN, OF BUFFALO, NEW YORK, ASSIGNOR TO FEEDERS MANUFACTURING COMPANY, INC., OF BUFFALO, NEW YORK

CAR HEATER

Application filed January 8, 1931. Serial No. 507,501.

This invention relates to heaters adapted to be used on motor vehicles, such as automobiles and boats, and particularly to such heaters as are adapted to transfer heat from 5 the internal combustion engines, which power such vehicles, to the passenger compartments thereof.

This invention comprehends an improved device having the water of the engine cooling system as its heating medium, which is adapted to effect a circulation and heating of air throughout the vehicle body.

The invention also has reference to a construction wherein the actuating motor of the 15 impeller means may be disposed within the confines of the heating radiator. The core of the latter may be of the type having a plurality of independent and substantially vertical water passages extending from the 20 top to the bottom thereof. In order to allow communication through such passages as may lie above and below the inset motor, a novel mounting for the motor has been devised which affords a passage about the motor 25 for connecting such passages.

Other features of the invention are the inclusion of a mechanical impelling device for effecting the circulation of the heated air, and thermostatic means for controlling 30 the operation of the impelling device.

These and other objects and advantages will become apparent through the perusal of the following description of a typical embodiment of the principles of the invention, 35 reference being made to the following drawing wherein:

Fig. 1 is a perspective view showing the improved heating element mounted upon the dashboard of a motor vehicle, parts of the 40 latter being broken away.

Fig. 2 is a central vertical cross-sectional view through the complete heating device assembly.

Fig. 3 is a rear elevational view of the 45 heating and impelling units of the assembly shown in Fig. 2.

Fig. 4 is a perspective view of the portion of the heating unit which serves to support the impelling unit.

Fig. 5 is a rear elevational view of the

motor of the impelling unit showing the thermostatic control means mounted thereupon.

As shown in Fig. 1 the heating element 10 is mounted upon the dashboard 11 which partitions the seating compartment 12 from the compartment containing the internal combustion unit 13. The latter may be of conventional design, having a water-jacket 14 surrounding the cylinders. A conduit 15 connects the water-jacket to the upper portion of a water-cooling radiator 16, and a conduit 17 connects the lower portion of the radiator 16 to the water-jacket allowing water in the jacket to be cooled by circulation through the 65 radiator. A motor driven pump 18 may be disposed along the conduit 17 to effect a positive circulation of the cooling water. Inlet and outlet conduits, 19 and 21, may be attached respectively to an upper portion of the 70 jacket 14 and a portion of the circulatory system between the radiator and conduit, and may extend through the dashboard 11 to the heating unit 10.

The latter includes a heating element or 75 core 22 comprising an upper water tank 23, a lower water tank 24, and a plurality of water-tube defining sections disposed between and connecting the water tanks. The lateral sections, 25 and 26, preferably comprise a 80 plurality of juxtaposed strips, each of which is deformed to provide continuous water passages from the upper to the lower tank, and a plurality of air passages extending from the inner face 27 to the outer face 28 of the core. 85

The upper and lower intermediate sections, 29 and 31 respectively, may be of the same formation as the sections 25 and 26, and communicate respectively, with the upper and lower water tanks. As shown in Fig. 3, the 90 lower and upper ends of the sections 29 and 31 are spaced to provide a substantially cubical space within the confines of the sections 25, 26, 29 and 31. A pair of plates, 32 and 33 connected by a tubular member 95 34 which may be secured in any suitable manner to the flanged apertures of the plates, are disposed in the space between the sections, the plate flanges 36 abutting the edge portions of the sections and preferably 100

being soldered thereto. A passage is, therefore, formed between the sections 25 and 26 and the tubular member 34, which connects the sections 29 and 31 for permitting communication through the water passages of the sections 29 and 31 between the upper and lower water tanks.

The latter are connected, respectively, to the inlet and outlet conduits, 19 and 21, as is depicted in Fig. 2 of the drawing. A pair of side plates 37 are secured along the side edges of the sections 25 and 26, and may have lateral extensions 38 for abutment with the dashboard 11 for supporting the core with its inner face spaced from the dashboard. The air impelling unit may comprise an electric motor 39 which may be disposed within the tubular member 34, and a plurality of impeller blades 40 mounted on the motor shaft. The impeller blades lie adjacent the outer surface 28 of the core and are adapted, upon rotation by the motor 39, to draw air from the vehicle interior through the space between the dashboard and the core, through the air passages of the core, and to force the air outward into the car interior.

A casing or hood 41 is disposed over the core and impeller assemblies and is provided with a central screen or grill 42, in alignment with the impeller, which while permitting of the passage of air from the heating unit, will prevent movement of objects, or portions of a human anatomy into contact with the impeller blades. As shown in Figs. 1 and 2, the hood proper is spaced from the dashboard to allow the circulation of air between the heating unit and the dashboard, and is supported by forward extending flanges 43 which overlie the side plate flanges 38 and which may together with the latter be secured to the dashboard 11 by bolts or other fasteners 44.

As shown in Figs. 3 and 4, the motor 39 is supported within the tubular member 34 by brackets 45 which may be secured to the tubular member or formed integrally therewith. Space is provided between the motor and the tubular member to permit of the passage of air from the space between the core and the dashboard over the motor by the action of the impeller. A thermostatic control unit is mounted upon the forward face of the motor, and is interposed in the electric actuating circuit of the motor to cause the motor to be automatically stopped when the temperature of the air within the vehicle reaches a predetermined degree. The thermostatic control unit may comprise a bi-metallic member 46 of convolute form, and electrically connected to one terminal 47 of the motor, and a contact member 48 which may be connected to one lead of the motor actuating circuit. The other terminal 49 of the motor may be connected to the other lead of the circuit.

In operation the motor will be actuated by

energy conducted through the actuating circuit, the bi-metallic element contacting the member 48 to close the circuit, and will rotate the impelling blades to draw air from the interior of the vehicle body about the motor 39 and through the air passages of the core, as indicated by the arrows in Fig. 2. When the air within the interior of the car has been heated, by circulation through the core passages, to a predetermined degree it will upon re-circulation pass the motor and thermostatic control unit and heat the element 46 sufficiently to cause the convolutions of the latter to be contracted, thereby breaking the contact between the member 41 and the contact 46, opening the motor circuit, and discontinuing the action of the motor and impeller. A thermostatically controlled valve 50 may be installed in the conduit 15 between the engine and the engine cooling radiator to automatically prevent cooling of the water within the jacket 14 to a temperature lower than that desired for circulation through the heating unit. Such a valve will also serve to decrease the time required, after starting the engine, to raise the temperature of the heater to a satisfactory degree.

In order to positively conduct an appreciable volume of heated air over the vehicle windshield 51, a conduit 52 is provided having an enlarged discharge opening 53 adjacent the bottom inner surface of the windshield, and an inlet end 54 attached to a nipple 55 which opens into the path of discharge from the impeller and which may be attached to or formed integrally with the hood 41.

By this construction the air to be heated is drawn entirely from within the vehicle interior; is forced through the heating element; and is expelled again into the car interior; so that no extraneous matter, such as dust, or noxious fumes, may be drawn into the car interior from the engine compartment or the outside atmosphere. The heated air discharged against the windshield for melting frozen moisture thereon passes into the car interior and is again returned for recirculation by the heating element. It will be understood that the thermostatic control unit is positioned forward of the passage between the motor and the tubular member 34, in such manner that the air passing by it will reflect the degree of temperature within the vehicle interior and may thus function to cut out the actuation of the impeller when that temperature has reached a predetermined degree. It will further be understood that the plates 32 and the tubular member 34 define with the core sections 25 and 26 a passage for heating water from the section 29 to the section 31, so that heating water may have an uninterrupted flow from the upper water tank to the lower water tank through all the core sections.

It will still further be understood that the device herein described and illustrated is merely exemplary of the principles of the invention which may be employed in other structural embodiments, and it is, therefore, intended that the invention be considered of scope commensurate with the appended claims.

What is claimed is:—

10 1. An air heating and circulating device comprising a pair of spaced sections, each having a plurality of water passages and a plurality of air passages, members connecting said spaced sections and defining a cavity between said sections, plates extending between said members and said sections, a tubular member of smaller cross-section than the area of either of said plates connecting said plates, the water passages of one of said sections communicating with the water passages of the other one of said sections through a passage defined by said sections, plates, members, and tubular member, and air-circulating means associated with the aforementioned elements, a portion of said air-circulating means being disposed within said tubular member.

2. An air heating and circulating device comprising a pair of water containers, a pair 30 of spaced sections each joined to each of said containers, each of said sections having a plurality of air passages extending therethrough and a plurality of water passages in communication with each of said containers, and means extending between said sections for supporting a motor within the confines of said containers and said sections, and air impeller means operable by said motor adjacent one face of said sections.

40 3. An air heating and circulating device comprising a pair of water containers, a pair of spaced sections each joined to each of said containers, each of said sections having a plurality of air passages extending from one face to an opposite face of said device and a plurality of water passages in communication with each of said containers, a second pair of spaced sections, each of the latter lying between said first pair of sections and being joined to one of said containers, each of said second pair of sections having a plurality of air passages extending from one face to an opposite face of said device and a plurality of water passages in communication with the container to which it is joined, and members extending between said pairs of sections along the opposite faces of said device for providing a chamber communicating with the water passages of said second pair of sections, a motor within said chamber, and an impeller operable by said motor to circulate air through said air passages.

4. An air heating and circulating device comprising a pair of spaced sections each having a plurality of air passages extending from

one to an opposite face of the device and a plurality of water passages, members extending between said sections for providing a chamber communicating with the water passages of both sections, a motor within said chamber, and an impeller operable by said motor to circulate air through said air passages, the minimum cross-sectional area of the water passage provided by said chamber being at least substantially equal to the combined area of the water passages of either one of said sections.

5. An air heating and circulating device for attachment to an interior surface of a motor vehicle body and comprising an air heating element spaced from said surface, an impeller for circulating air from the space between the heating element and said surface through the air heating element and about in the vehicle body, an electric motor for operating said impeller, said motor being disposed within the confines of the air heating element, and an electric circuit for actuating said motor, including a thermostatic circuit breaker mounted upon said motor and disposed in said space for opening the circuit when the air in the vehicle body becomes heated to a predetermined degree.
